UNITED STATES PATENT OFFICE

ARTHUR G. MCKEE, OF CLEVELAND, OHIO

BELL ROD SWIVEL SUPPORT

Application filed January 29, 1931. Serial No. 511,969.

This invention relates to blast furnaces and, more particularly, to an improved swivel joint for the small bell rod of blast furnace tops of the revolving distributor type.

- 5 In charging ore, coke and limestone into the top of a blast furnace it is important that the charges be distributed as evenly as possible. This even distribution is facilitated by the use of what is commonly known as the 10 revolving distributor top. In the operation of this type of apparatus a charge of material is dumped from the skip car into a revolvable distributor chamber or hopper. As the skip car dumps into this revolvable hopper from 15 one side, the tendency is for the load to be positioned more on one side of the hopper than on the other. It is undesirable to transfer this unequal loading to the large bell as this would result in uneven distribution of 20 the charge in the furnace. To prevent this the distributor hopper, after the skip car has been dumped into it, is rotated a certain amount and the charge then dropped upon the large bell. Each successive hopper load is 25 rotated a different amount before it is dropped on the large bell and thus the large bell will receive a uniformly distributed charge. The small distributor closing bell is then closed and the main bell lowered allowing the uniformly distributed charge to drop into the 30 furnace. In the construction of this type of furnace top, it is ordinary practice to have the bell rod which operates the large bell extend up through a hollow concentric bell rod which 35 operates the small bell. As this small bell must necessarily rotate with the revolving distributor it becomes necessary to provide some sort of swivel joint in the tubular small bell rod. This joint must withhold the 40 weight of the bell and the weight of the charge deposited thereon and, as it operates in an atmosphere which is constantly laden with ore, coke and limestone dust, it is important that this swivel joint be absolutely dust tight. It 45 is also important that this joint be so constructed that it may be removed and replaced without having to remove the large bell or otherwise disturbing the furnace top structure.

50 It is among the objects of my invention

therefore, to provide a swivel joint for the small bell rod of a revolving distributor blast furnace top which is absolutely dust tight and which may be easily repaired or replaced without removal of other parts of the blast 55 furnace structure and without interfering with the maintenance of the blast furnace operation.

A further object of my invention is the provision of a swivel joint for blast furnace 60 bell rods in which friction and wear are reduced to a minimum.

A further object of my invention is the provision of a bell rod swivel joint which will last during the entire campaign or running 65 period of a furnace without repair or replacement.

The above and other objects of my invention will be seen from the following description of a preferred form thereof, reference 70 being had to the accompanying drawings in which:

Fig. 1 is a sectional view of a blast furnace top of the revolving distributor type.

Fig. 2 is a vertical, longitudinal sectional 75 view of my improved swivel bearing.

Fig. 3 is a cross section of the swivel joint taken on line 3—3 of Fig. 2.

Fig. 4 is a cross section taken on line 4—4 of Fig. 2. 80

Fig. 5 is a cross section taken on line 5—5 of Fig. 2.

Fig. 6 is a cross section taken on line 6—6 of Fig. 2.

In Fig. 1, the essential parts of a revolving distributor type of blast furnace top are illustrated. The top of the furnace 1, carries the main charging chamber 2 which is adapted to be closed by the large bell 3. The revolving distributor chamber 4, which is preferably cylindrical, is rotatably mounted at 5 on the top of the main charge chamber 2. The distributor 4 may be rotatably supported in any suitable manner. A bevel ring gear 5' is secured to the outside of the distributor 4 and is adapted to be engaged by a small bevel gear 5''. The bevel gear 5'' may be driven by any suitable means such as a motor M to rotate the distributor 4. This rotating distributor extends down into the main 95 100

charging chamber 2 and is adapted to be closed by the small bell 6. The charges of ore, coke and limestone which are discharged from the skip hoist 7, drop into the distributor 4 through the non-rotating hopper 8.

The large bell 3 is supported by the bell rod 9 which extends upwardly and is pivotally connected by suitable linkage to the beam 10. This beam is counterweighted at 10 11 and may be provided with any suitable means (not shown) for raising and lowering the bell hopper. The small bell 6 is supported by the tubular bell rod 12 which surrounds the bell rod 9 of the large bell 3 and is 15 pivotally connected by the links 13 to one end of the pivoted counterweighted beam 14. It will be understood that suitable means (not shown) for moving the arm 14 to lift and lower the small bell may be provided.

20 I have illustrated a number of wear rings 15 which are slipped over the tubular bell rod 12 and serve to prevent undue abrasive wear on the bell rod 12 due to the flow of slag, ore, and coke thereover. The small bell 25 6 is adapted to rotate with the rotating distributor 4 and, to facilitate and permit this rotation, a swivel joint, generally indicated at 16, is provided in the tubular small bell rod 12.

30 From the position of the swivel joint 16 as illustrated in Fig. 1, it will be seen that this joint must support the weight of the bell 6 and the bell rod 12 together with the weight 25 of the charge which is deposited in the rotating distributor 4. As it is located directly above the open top of the hopper 8, it is subjected to the abrasive action of the dust, which necessarily arises when the skip hoist 7 is dumped.

40 Referring now to Figs. 2, 3, 4, 5 and 6, my improved swivel joint includes a pair of split lower sections A and a pair of split upper sections B. The two lower sections are secured firmly together by the bolts 17 and 18 to form 45 a substantially tubular member into the lower end of which the tubular small bell-rod 12 may be suitably secured as by the screw threads indicated at 19. The bell-rod 9 which supports the large bell 3 extends up 50 through the cylindrical opening in the lower sections A and the parts are so proportioned that the large bell rod 9 may move freely through the central opening in the swivel joint of the small bell rod. A circular flange 55 20 having flat top and bottom surfaces is formed on the parts A approximately midway of their ends.

The upper members B surround the tubular upwardly extending part 21 of the members 60 A above the flange 20 and are flared outwardly to form an inverted cup-shaped portion 22 in which the flange 20 lies. The members B may be secured together by suitable bolts 40. Secured to this inverted cup-shaped portion 65 22 of the parts B is a split cup-shaped mem-

ber 23 which is secured to the members B by the bolts 24. The lower end of the cup-shaped member 23 is provided with an aperture in which the lower cylindrical portion of the members A has a relatively close fit. 70 The joints between the members A and the cup-shaped part 23 are adapted to be made dust tight by the packing 25, which may be held in position by the adjustable ring 26 in well known manner. This packing gland 75 forms a dust tight joint between the non-rotating upper members B and the rotatable lower members A and prevents the entry of dust through the bottom joint to the bearing.

Rings of packing 27 and 28, which are disposed between the non-rotating parts B and the rotatable inner member A serve to form dust tight joints between the upper ends thereof.

To reduce friction as much as possible, I 85 have provided a roller type of thrust bearing which is disposed between the flange 20 and the bottom portion of the cup members 23. A plurality of rolls 29 are disposed between hardened steel races 30 and 31. These rolls 90 29 are separated and held in their proper positions by the separator 32 (Fig. 4). The races 30 and 31 are each split into two parts, as are all of the parts of my improved joint. As best seen in Figs. 5 and 6, the splits in the 95 races are made at an angle to the radial line through the point of the split so that vibration and wear caused by the rolls passing over the joints between the two halves of the races will be reduced to a minimum.

100 Trunnions 32 and 33 are formed on the non-rotating upper part B of the joint and form bearings for the links 13 which connect the joint to the ends of the counterweight lever 14.

105 The roller bearings may be lubricated through suitable holes 34 and it will be seen by those skilled in the art that I have provided an improved swivel joint construction 110 which may be easily assembled and taken down, and which is particularly adapted for use in rotating distributor top blast furnaces.

115 Although I have illustrated and described one embodiment of my invention in some detail, it will be seen by those skilled in the art that variations and modifications may be made in my invention without departing from the spirit thereof. I do not therefore, limit myself to the precise details shown and described, but claim as my invention all embodiments thereof coming within the scope of the appended claims.

I claim:

120 1. In combination, a tubular bell rod, means for operating said bell rod, a tubular member secured to the upper end of said bell rod and having an outwardly extending flange portion, an outer tubular member having a cup-shaped portion enclosing said 125 130

- flange, said outer tubular member having link connection to said means for operating said rod, and a roller bearing between said flange and the cup-shaped portion of said outer tubular member adapted to sustain the load on said bell rod and to permit free relative rotation between said tubular members.
2. In combination, a tubular bell rod, means for operating said bell rod, a tubular member secured to the upper end of said bell rod and having an outwardly extending flange portion, an outer tubular member having a cup-shaped portion enclosing said flange, said outer tubular member having link connection to said means for operating said rod, and a roller bearing between said flange and the cup-shaped portion of said outer tubular member adapted to sustain the load on said bell rod and to permit free relative rotation between said tubular members and packing means for preventing the entry of dust to said cup-shaped member and said bearing.
3. In combination, a tubular bell rod, means for operating said bell rod, a tubular member secured to the upper end of said bell rod and having an outwardly extending flange portion, an outer tubular member having a cup-shaped portion enclosing said flange, said outer tubular member having link connection to said means for operating said rod, and a roller bearing between said flange and the cup-shaped portion of said outer tubular member adapted to sustain the load on said bell rod and to permit free relative rotation between said tubular members and packing means for preventing the entry of dust to said cup-shaped member and said bearing, each of the parts of said swivel joint being split, whereby they may be assembled and disassembled about a central rod extending through said tubular member.
4. A swivel joint of the type described, comprising a tubular member having an outwardly extending flange, a second tubular member concentrically enclosing said flange and rotatable relative thereto, a roller thrust bearing between said flange and said second tubular member and means for sealing said bearing against the entry of dust thereto.
5. A swivel joint of the type described comprising an outer tubular member and an inner relatively rotatable tubular member, a roller thrust bearing adapted to maintain said members in spaced relation and means for sealing said bearing against the entry of dust thereto.
6. A swivel joint comprising relatively rotatable portions with a thrust bearing therebetween, said thrust bearing including a pair of split races and a plurality of rollers disposed between said races, each of said races being split into two parts on non-radial lines.
7. A swivel joint comprising relatively rotatable portions with a thrust bearing therebetween, said thrust bearing including a pair of split races and a plurality of rollers disposed between said races, each of said races being split into two parts on non-radial lines and means for sealing said bearing against the entry of dust thereto.
8. In a swivel joint for blast furnace bell rods, the combination of an annular roller bearing having non-radially split races, a split cylindrical member extending through said bearing and having an outwardly extending flange adapted to engage one of said bearing races, an outer split cylindrical member disposed around said first named cylindrical member, said outer cylindrical member being adapted to enclose said flange and bearing and having a portion adapted to engage the other of said bearing races, packing means between said cylindrical members on each side of said bearing and trunnions on said outer member.
9. A swivel joint comprising a flanged tubular member, an outer tubular member disposed about and enclosing the flange of said first named tubular member and a roller thrust bearing enclosed within said outer member and adapted to separate said tubular members whereby they are freely rotatable relative to each other.
- In testimony whereof I hereunto affix my signature this 19th day of January, 1931.
- ARTHUR G. MCKEE.
